Filed Dec. 23, 1971, Ser. No. 211,852

Term of patent 14 years

Int. Cl. D10—01

U.S. Cl. D42—8 R

FIG. 1 is a perspective view of a table clock showing my new design;

FIG. 2 is a top plan view thereof;

FIG. 3 is a perspective view of another embodiment of my new design of FIG. 1 wherein the casing is square rather than round.

The circular indicia bearing rings within the housings are of very thin transparent material.

I claim:

The ornamental design for a table clock, as shown and described.
